H. G. LYKKEN

PULVERIZING DEVICE AND METHOD

Filed Nov. 3, 1924

Inventor:
Henry G. Lykken,
by Wallace Polane.

UNITED STATES PATENT OFFICE.

HENRY G. LYKKEN, OF MINNEAPOLIS, MINNESOTA.

PULVERIZING DEVICE AND METHOD.

Application filed November 8, 1924. Serial No. 747,486.

The present invention relates to the treating of pulverized materials, such as by the conducting of the materials in a finely divided and suspended state and in a more or less fluidal condition.

In the specific method and form of device selected to illustrate the invention, the pulverized material is carried in suspension in a stream of air from the pulverizing means 10 to the place of use or consumption. The invention comprehends the treating of the material while being so conducted so that there may be an equalization or distribution of the rate of movement or flow of the material, thus 15 avoiding concentrated currents and the carrying of the coarser with the finer particles to the locus of use, and also includes the separating out of the coarser particles which may be collected and discharged for re-pulverizing, 20 if desired.

Among the objects of the invention are to provide a novel device for equalizing the flow of the fluidal material in a passage by the use of porous means, such as screens or the 25 like, preferably removably located in the passage in the path of flow of the material so that the rate of flow thereof may be partly checked to effect an equalization of the rate of flow at all points of the stream or throughout the 30 cross-sectional area thereof; to provide for separating out, preferably during the flow checking, of the coarser particles, the particles, in a specific form of the device, being capable of moving by gravity over inclined 35 screens to the lower ends thereof where the particles may be collected in a chute and discharged to the exterior of the passage or returned to the pulverizing device for further reduction; to provide for a plurality of porous means, preferably spaced, for effecting 40 the desired amount of checking and equalization; to provide the screens with openings greater in size than the size of the particles being carried by the stream of air; to provide 45 means for removably and preferably slidably, supporting the screens and also providing the passage or chamber with an opening or slot through which the screens may be inserted or withdrawn; to provide for a closure 50 for such opening; and to provide for such other objects, advantages and capabilities as may later appear and which are inherently possessed by the invention.

In the drawing, illustrating a form of device constructed in accordance with the invention, Figure 1 is a vertical section of the

device; and, Figure 2 is a vertical sectional view of a detail.

Referring more particularly to the drawing, the embodiment selected to illustrate the invention comprises a hopper 1 in which the material is placed preparatory to being crushed between a crushing roll 2 and a plate 3 from whence the crushed material may be fed into the chamber 4 to a feeding roll 5 designed to feed the crushed material into the opening 6 in the upper part of the grinding mechanism 7. The latter comprises suitable relatively movable grinding elements 8 and 9 suitably associated so that the material 10, fed into the grinding mechanism, may be acted upon by the members, preferably by a mulling action, and when ground and pulverized may be cast in the direction of the arrows 11 against an adjustable plate 12 as clearly shown in Figure 1 of the drawing.

Air is drawn in through an opening 13 and passes upwardly through the opening 6 and the material being discharged by the rotor of the pulverizer, the air thus acting 80 to separate the finer particles from the material being projected from the grinder rotor, and carrying the same upwardly into an expansion chamber 14. At the same time the stream of air will pass through the clouds 85 of pulverized material being reflected from the plate 12 and also separate therefrom the finer particles of pulverized material to be carried upwardly in the stream of air.

The chamber 14 has an inlet 15 communicating with the space or opening 6 in the upper part of the grinding and pulverizing mechanism and has an outlet 16 leading to a point of use or consumption where a suitable suction or vacuum is produced for causing a drawing of the air through the chamber 14 and the opening 6 from the opening 13. Intermediate the inlet and outlet of the chamber may be located one or more screens 17 preferably of sheet material, such as metal, 95 provided with perforations or openings 18 of substantial size greater than the particles of material being carried upwardly by the stream of air. These sheets are preferably carried upon frames 19 movably and slidably supported upon supporting elements 20 suitably secured to the side walls of the chamber 14. These screens are preferably located transversely of the path of flow of the air and pulverized material and substantially 100 completely across the space in the chamber 14. They are also preferably inclined with 105 110

the lower ends thereof located in an opening 22 formed in one of the walls 23 of the chamber. The opening 22 is preferably normally closed by a cap or closure member 24 having flanges adapted to have a sliding fit with the flanges 26 surrounding the opening 22. The cap 24 will perform the double function of closing the opening 22 and holding the screens in position. The screens may be inserted or removed through this opening by sliding the same over the supporting elements 20. Near the lower ends of the screens and between the frame parts and the perforated sheets, may be provided suitable openings 27 through which the larger particles of material which may move gravitationally over the sheets 18 toward the lower end of the screens, may pass downwardly through these openings 27 and into a chute 28 formed between the wall 23 and an auxiliary wall 29. The lower end of the chute extends into an outlet passage 30 having an adjustable plate or trap door 31 so located that the suction produced in the chamber 14 will not be broken by the opening 30 but will permit the downward flow of the accumulated particles of material so the same may be discharged into the chamber of the grinding and pulverizing mechanism and again acted upon for further reduction.

At the upper end of the chamber 14 may be provided a door 34 of any suitable form for giving access into the chamber. At the lower end of the chamber is provided a safety gate 32 supported upon a rod 33 near the feeding roller 5 such that if any non-crushable matter should be forced through the passage from chamber 4 to the opening 6 by the crusher roller 5, the safety gate 32 may yield and permit the passage of the non-crushable material.

In operation, the material being ground and pulverized is cast in the direction of the arrows 11 across the upwardly moving stream of air so that the latter may separate out of the material fine particles of pulverized material and carry the same upwardly in suspended condition. The material cast upon the plate 12 will be reflected into the stream of air and the latter will further remove particles of material and carry the same upwardly in suspended state. If no provision were made for equalizing the rate of flow of the material throughout the width of the chamber 14, concentrated and local currents would occur so that the coarser material with the finer material would be carried through these currents into the outlet 16 and to the place of use. By providing the perforated screens in the path of movement of the air and suspended material, a checking effect is produced so that the stream will have an opportunity to be equalized so that the flow thereof at all points will be equal and evenly distributed. At the same time as the air and

suspended particles pass through the perforations 18 of the screens, the heavier particles will have an opportunity to fall upon the surface of the screens and travel downwardly over the inclined faces thereof into the openings 27 and into the chute 28. These heavier particles will accumulate in the passage 30 and be discharged into the pulverizing device. The air and finer particles will then pass, evenly distributed, into the outlet 16 and to the consuming means.

While I have herein described and upon the drawing shown one form of device for carrying out the invention, it is to be understood that the invention comprehends other constructions, details and arrangements of parts without departing from the spirit thereof.

Having thus described my invention, I claim:

1. A pulverizing apparatus comprising a pulverizing chamber provided with pulverizing means, an expansion chamber connected with the pulverizing chamber so that the pulverized material may be drawn thereinto, a screen positioned in the expansion chamber a substantial distance from the inlet opening of said chamber, said screen being extended approximately across the entire cross sectional area of the expansion chamber so as to equalize movement of the pulverized material through the last mentioned chamber.

2. A pulverizing apparatus comprising a pulverizing chamber having pulverizing means therein, an expansion chamber connected with the pulverizing chamber so that the pulverized material may be drawn thereinto, a screen positioned in the expansion chamber a substantial distance from the inlet opening of said chamber, said screen extending approximately across the entire cross sectional area of said expansion chamber so as to equalize movement of the pulverized material therethrough, and means adjacent one edge of the screen providing a shielded outlet for discharging into the pulverizing chamber the coarser particles which drop out of the stream of pulverized material.

3. A pulverizing apparatus comprising a chamber provided with pulverizing means, an expansion chamber connected with the pulverizing chamber so that the pulverized material may be drawn thereinto, an inclined screen positioned in the expansion chamber a substantial distance from the inlet opening thereof, said screen extending approximately across the entire area of the expansion chamber so as to equalize movement of the pulverized material therethrough, the lower portion of said screen being provided with discharge openings for the coarser particles which drop out of the stream of pulverized material, and means for directing said coarser particles to the pulverizing chamber.

4. A pulverizing apparatus comprising a

5 pulverizing chamber, an expansion chamber connected with the pulverizing chamber so that pulverized material may be drawn from the pulverizing chamber into the expansion chamber, a plurality of inclined screens positioned in the expansion chamber a substantial distance from the inlet opening of said chamber, said screens extending approximately across the entire cross sectional area 10 of said expansion chamber so as to equalize movement of the pulverized material therethrough, and means at the lower ends of said screens for directing into the pulverizing chamber the coarser particles which drop out 15 of the stream of pulverized material.

5. A pulverizing apparatus comprising a pulverizing chamber, an expansion chamber connected therewith so that pulverized material may be drawn from the pulverizing chamber into the expansion chamber, a plurality of spaced apart screens positioned within the expansion chamber a substantial distance from the inlet opening thereof, said screens extending approximately across the 15 entire cross sectional area of the expansion chamber so as to equalize movement of the pulverized material through the last mentioned chamber, frames for said screens, and means in the expansion chamber for removably supporting the screens, said chamber having an opening through which the frames may be removed or inserted in place.

6. A pulverizing apparatus comprising a pulverizing chamber, an expansion chamber connected therewith so that pulverized material may be drawn from the pulverizing chamber into the expansion chamber, a plurality of spaced screens located within the expansion chamber a substantial distance from the inlet opening of said chamber and extending approximately across the entire cross sectional area of said expansion chamber, so as to check and deflect the stream of pulverized material and thereby effect an equal flow of the stream in said expansion chamber, said screens comprising frames and porous sheets carried by the frames, means

in the expansion chamber for slidably supporting the frames, said chamber having an opening through which the screens may be 50 slid into and out of place in the chamber, and means for closing said opening.

7. A pulverizing apparatus comprising a pulverizing chamber provided with an air inlet opening, an adjustable deflecting plate 55 mounted adjacent said opening, an expansion chamber connected with the pulverizing chamber so that pulverized material may be drawn thereinto from said pulverizing chamber, a screen positioned in the expansion chamber a substantial distance from the inlet opening thereof and extending approximately across the entire cross sectional area of said chamber, a chute adjacent said screen to receive coarser particles which may pass said 65 screen, said chute having an outlet passage positioned to direct said particles into said pulverizing chamber.

8. A pulverizing apparatus comprising a pulverizing chamber provided with an air inlet opening, a deflector plate adjustably mounted adjacent said opening, means associated with said chamber for directing pulverized material against said deflector plate, an expansion chamber connected with the 75 pulverizing chamber so that pulverized material may be drawn by suction thereinto from the pulverizing chamber, a screen positioned in the expansion chamber a substantial 80 distance from the inlet opening of said expansion chamber, said screen extending approximately across the entire cross sectional area of said chamber, a chute for directing the heavier particles of pulverized material back to said pulverizing chamber, and means 85 associated with said chute for permitting downward flow of the accumulated heavier particles to the pulverizing chamber and preventing the breaking of the suction produced in said expansion chamber. 90

In witness whereof, I hereunto subscribe my name to this specification.

HENRY G. LYKKEN.
